DESIGN FOR A SCARF-PIN.

SPECIFICATION forming part of Design No. 23,827, dated December 4, 1894.

Application filed October 31, 1894. Serial No. 527,584. Term of patent 3½ years.

To all whom it may concern:

Be it known that I, GEORGE F. GREENE, a citizen of the United States, residing at Providence, in the county of Providence and State of Rhode Island, have invented and produced a new and original Design for Scarf-Pins, of which the following is a specification, reference being had to the accompanying drawing, forming a part thereof.

10 The head or ornamental portion of the scarf-pin has the outline, shape and appearance of a boy, in front view, sitting tailor-fashion, with a pan in his lap. In the pan there is apparently a pie, having an upwardly curved crust, broken at the top. His left hand is

holding the pan and his right arm is bent so as to bring the right hand centrally over the pan and on the thumb of said hand is a plum. His breeches extend to the knees and he has slippers on his feet. The pin tongue extends centrally downward from said ornamental portion or head.

What I claim is—

The design for a scarf pin herein shown and described.

GEORGE F. GREENE.
